FACSIMILE APPARATUS

Maurice Artzt, Haddonfield, N. J., assignor to Radio Corporation of America, a corporation of Delaware

Application August 25, 1942, Serial No. 456,000

17 Claims. (Cl. 178—13)

This invention relates to an improvement in facsimile systems, and, more particularly, to an improvement in the structural features of a facsimile transmitting apparatus.

A facsimile transmitter includes, broadly, a structure generally in the form of a rotating cylinder upon which the copy to be transmitted is positioned. This cylinder is then rotated at a predetermined constant rate, and during the rotation of the cylinder, a beam of light of reduced cross section is projected against the outside surface of the cylinder in order to perform a scanning action. Light reflection from the surface is then directed against a light responsive cell in order that the variations in reflected light will produce variations in the produced current representative of the subject matter appearing on the copy. As the drum is rotated, the spot of light and the photo-cell are moved longitudinally with respect to the drum in order that bi-dimensional scanning may be accomplished.

Simultaneously with the scanning operation, synchronizing or framing impulses are generated by appropriate means for providing a framing impulse for each revolution of the drum in order that facsimile receivers may be maintained in proper synchronous operation with respect to the transmitter. As is well known to those skilled in the art, the picture signals produced by the photo-cell or the light responsive element at the transmitter are, after appropriate amplification, transmitted to the receiver either by direct wire connection or by a radio link through the use of a modulated radio frequency carrier. Simultaneously, the synchronizing or framing impulses are transmitted to the receiver so that at the receiver the picture signals may be utilized to produce a facsimile copy of subject matter positioned on the scanner drum in the transmitter.

An electric motor is normally provided for rotating the scanner drum at the transmitter, and it is preferable that the motor operate at substantially constant speed in order to facilitate in maintaining synchronous operation at the receiver, since it might not be possible for the moving elements at the receiver to follow excessively rapid changes in speed of the scanner drum at the transmitter due to the mechanical inertia of the moving parts of the receiver.

Inasmuch as the copy must be attached to the scanner drum or wrapped around the exterior surface thereof, naturally the drum must be in a stationary position at the time the copy to be transmitted is placed in position to be scanned. Frequently it is not desirable to completely dis-

continue the operation of the transmitter, in which case it is preferable to be able to remove the scanner drum from the transmitter without the necessity of actually stopping the driving motor, and without discontinuing the transmission of the synchronizing or framing impulses. Furthermore, should the scanner drum be removed from the transmitter while the driving motor is still permitted to run, it is necessary to provide some means for again placing the scanner drum in the transmitter and for coupling the motor to the scanner drum in order that the drum may again be rotated at its normal scanning rate. In addition to imparting rotary motion to the drum, it is also necessary that the drum be properly phased with respect to the coupling or chuck mechanism for driving the drum, in order that the synchronizing signals will occur at proper time intervals with respect to each scanning revolution of the drum. This is because of the fact that the synchronizing or framing signals are normally derived from a continuously rotating part of the transmitter, and a proper phase relation or orientation of the scanner drum or cylinder is necessary with respect to the chuck associated with the drum.

Accordingly, it is one purpose of the present invention to provide in a facsimile transmitter, structural means whereby it is possible to remove the scanner drum from the transmitter without the necessity of discontinuing the operation of the driving motor.

Another purpose of the present invention resides in the provision of means for again positioning the scanner drum in the transmitter while the driving mechanism is in operation.

Still another purpose of the present invention resides in the provision of means whereby the facsimile transmitter scanner drum may be brought up to proper rotational speed through the use of a clutch mechanism, and after proper rotational speed is obtained further means are provided for properly framing or phasing the position of the scanner drum with respect to the chuck driving mechanism.

A still further purpose of the present invention resides in the provision of a tail stock assembly for supporting the end of the scanner drum opposite the driven end such that the scanner drum may be rotated and such that the scanner drum may be released from both the chuck mechanism and the tail stock after the scanning operation has been completed.

Still another purpose of the present invention resides in the provision of a tail stock assembly

which may assume any one of three positions, one of the positions being the released or inoperative position, another position being the starting position during which time the scanner drum is brought to proper rotational speed, and the third position being the running position in which the scanner drum is properly phased rotationally with respect to the driving clutch.

Various other purposes and advantages of the present invention will become apparent to those skilled in the art from the following detailed description and claims, particularly when considered in connection with the drawings, wherein like reference numerals represent like parts and wherein

Figure 1 shows a preferred form of the present invention with the clutch assembly, the scanner drum and the tail stock assembly in the starting position;

Figure 2 shows the present invention with the clutch assembly, the scanner drum and the tail stock assembly in the running or scanning position;

Figure 3 shows an end view of the clutch assembly for driving the scanner drum; and

Figure 4 shows a perspective view of one end of the scanner drum.

Referring now to the drawings, and particularly to Figure 1 thereof, a facsimile transmitter scanning drum 10 is provided upon which is positioned the copy to be transmitted. Normally the copy is wrapped about the periphery of the drum and is retained in position thereon by means of an appropriate securing means 12. Inasmuch as the present invention is not concerned with the specific construction of the scanner drum or the structure supporting the paper, that portion of the drum intermediate the ends thereof will not be described in detail, and, furthermore, for simplicity and in order to conserve space only the end portions of the drum are shown.

The live spindle or driven end of the drum includes a central axial aperture or recess which serves as a bearing member, the recess being lined with an appropriate bearing surface such as brass or "Oilite" 13. Attached to the end of the scanner drum is a circular plate 14, the plate being secured to the drum by means of a plurality of screws or other appropriate fastening means 16. The plate member 14 or the end face of the scanning drum is provided with a radial notch or recess 18, the purpose of which will be explained later.

The opposite end of the scanner drum has a reduced portion 20 which is bored along its axis to provide a bearing, and an appropriate bearing surface 22 similar to the bearing surface 13 on the opposite end of the drum is provided.

The mechanism for driving the scanner drum includes a motor 24 which is coupled to the shaft 26. The shaft is supported by an appropriate bearing surface 28 attached to a wall structure 30. A sleeve 32 is attached to the shaft by means of a pin 34. The sleeve is provided with an annular driving member 36 which forms one face of a clutch mechanism. A ball bearing, including an internal race 38 and an external race 40, is slidably positioned on the sleeve 32 in order that it may move axially with respect to the sleeve. Attached to the external race 40 of the ball bearing is an annular driven member 42, and a cap disk 44 is attached to the annular member 42 by means of screws or other appropriate fastening means 46 in order that there can be no relative motion between the annular member 42 and the external race 40 of the ball bearing.

The annular member 42 includes two plane faces normal to the axis of the sleeve 32 and normal to the axis of the shaft 26. One of these faces is provided with a clutch facing 48, and the other is provided with a clutch facing 50. These two clutch facings may be made of leather or other appropriate material, the facings being attached to the annular member 42 by means of cement or other appropriate securing means. The clutch facing 48 normally cooperates with the annular driving portion 36 of the sleeve 32 in order that the rotation of the sleeve 32 may impart a rotary motion to the annular driven member 42. The clutch face 48 is held in cooperating contact with the annular member 36 by means of a compression spring 52 which is positioned between the longitudinally slideable ball bearing race 38 and a collar 54 that is permanently attached to the sleeve 32 by means of set screws 56. When no force is applied to the annular driven member 42 to separate the clutch face 48 from the annular driving member 36, the clutch will cause the annular driven member 42 to rotate with the main driving shaft 26.

The clutch face 50 is arranged to cooperate with the plate 14 that is attached to the end of the scanner drum 10. In order that the scanner drum may be guided into proper position and may be axially aligned with the main driving shaft 26, the end of the shaft 26 adjacent the scanner drum is tapered slightly in order to act as a guide when the bearing surface 13 is brought into contact with the end of the shaft 26. When the scanner drum is forced against the clutch facing 50 by means of the tail stock assembly, the construction of which will be explained later, a rotary driving force for imparting a rotary motion to the previously stationary scanner drum will then be transmitted from the motor 24 through the shaft 26, pin 34, sleeve 32, the clutch including face 48 and annular driving member 36, through the annular driven member 42 to the clutch face 50. This will permit the scanning drum to be brought up to proper rotational speed corresponding to the speed of the main driving shaft 26.

The rotating sleeve 32 has attached thereto a somewhat resilient spring support member 62 which is substantially semi-circular in shape, the ends of the semi-circular spring member 62 being attached to the sleeve 32 by means of screws or other appropriate securing means 64. The spring support member 62 has attached thereto a roller 58, the roller being secured by means of a bolt and nut 60 or other suitable means. In Figure 3 is shown an end view of the clutch, and in this view the relationship of the roller 58 and the associated elements for supporting the roller are clearly shown.

The roller is arranged to cooperate with the radial notch 18 in the face 14 of the end of the scanner drum. After the scanner drum is brought up to proper rotational speed, further longitudinal movement of the scanner drum in the direction of the clutch mechanism will move the annular member 42 longitudinally, thereby stressing and compressing the spring 52 by forces transmitted through the ball bearing. This operation disengages the clutch face 48 from the driving clutch face 36, permitting the scanner drum to be disengaged from the driving mechanism. As the scanner drum begins to slow down, by reason of the disengagement of the clutch,

the roller 58 (which is then in contact with the face of the plate 14) will eventually drop into the radial recess 18, thereby fixing the relative rotational position of the scanner drum with respect to the driving shaft 26 and the sleeve 32, since the roller 58 is permanently attached to the sleeve 32. Rotational forces will then be transmitted through the semi-circular spring member 62 and the roller 58 to the end face 14 of the printer drum, inasmuch as the roller 58 is then positioned in the recess 18.

Figure 2 shows the final or running position of the clutch mechanism with the scanner drum cooperating with the roller 58. In Figure 2, the elements have applied thereto the same reference numerals as are applied to the corresponding parts in Figure 1. When the scanner drum is in its final operating or running position, it will be noticed that the end of the shaft 26 extends an appreciable distance into the bearing 13 in order to rigidly support the scanner drum, and in order to prevent any possibility of radial movement of the drum. In the running position, as shown in Figure 2, the clutch faces are not effective for transmitting rotational forces (since clutch face 48 is disengaged from the cooperating driving member 36), nor is the roller bearing 38-40 in operation since the entire clutch mechanism then rotates as a unit.

For imparting the desired longitudinal movement to the scanner drum in order to operate the clutch mechanism as described above, a tail spindle structure is used such as shown at the right hand portion of Figures 1 and 2. Through the operation of this tail structure, the scanner drum may be moved the proper longitudinal amount in order to bring the scanner drum up to its proper rotational speed during the starting interval, and in order to subsequently bring the scanner drum into proper cooperative position with the roller 58 in order that the scanner drum may be properly phased and positively driven by means of this cooperation.

The tail spindle structure includes a shaft 70 which is supported in a housing or other stationary structure 72. On the shaft 70 is positioned a slidable cylinder 74, the cylinder 74 being normally urged against a shoulder 76 made integral with the shaft 70. The shoulder 76 may, however, be in the form of a ring retained in proper position by means of set screws. The cylinder 74 is urged against the shoulder 76 by means of compression spring 78, the spring cooperating with a ring 80 secured to the rod 70. Another ring 82 is also provided for limiting motion of the rod 70 in the direction toward the right in the drawings, and normally the rod 70 is urged in that direction by means of compression spring 84. This spring is positioned between the wall 72 and a shoulder or washer 86 at the end of the rod 70.

In the normal released position of the rod 70, the spring 84 urges the rod in its extreme right position, indicated by the dotted end portion of the rod 70 in Figure 2, whereas in the starting position the shaft occupies a position such as indicated in Figure 1. When the facsimile transmitter is in its final running or operating position, the shaft 70 is in a position such as indicated in Figure 2.

In order that the rod 70 may be moved the desired amounts, a ratchet mechanism is provided. The cylinder 74 is provided with two annular grooves 88 and 90 with which cooperate two pawls 92 and 94. The pawl 92 is pivoted on an oper-

ating lever 96 at the pivot point 98, while the operating lever is pivoted on the pin 100. In order that the pawl 92 may be urged in the direction of the cylinder 74, a tension spring 102 is connected between the pivot point 100 and the end of the pawl lever 92. Furthermore, in order that the operating lever may be retained in its normal position, a second tension spring 104 is connected between the pivot point 98 (or the end of the operating lever 96) and a stationary part of the housing or the wall 72.

When the tail stock mechanism is in its complete "off" or disengaged position, indicated by the dotted end portion of rod 70 in Figure 2, the pawl 92 normally rests in a position to cooperate with the annular ring 88. Actually, the pawl 92 is not permitted to touch the cylinder 74 when the operating handle is in its released position, since the stationary vertical pin 106 cooperates with the pawl 92 to prevent the operating end of the pawl from cooperating with the cylindrical member 74 until after some initial movement has been imparted to the operating lever 96. When the operating lever 96 is moved in a counter-clockwise direction about the pivot point 100, the pawl 92 engages the annular ring 88 to slide the rod 70 forward a predetermined amount against the action of spring 84, the sliding force being transmitted through the somewhat stronger spring 78. The pawl 94 then drops into the annular ring 88 to retain the rod 70 in that position. The pawl 94 is pivoted about point 108, and this pawl is urged in the direction of the cylinder 74 by means of compression spring 110.

This operation causes the end face 14 of the scanner drum to engage clutch face 50 to cause rotation of the drum through clutch 36-48. After the scanner drum has been brought up to its proper rotational speed, the operating handle is then again rotated in a clockwise direction at which time the pawl 92 cooperates with the annular groove 90, as indicated in Figure 2, to further slide the rod 70 toward the left to thereby axially move the scanner drum in the corresponding direction to disengage clutch faces 48 and 36. Relative rotational motion between the scanner drum and the driving member 36 is then permitted until the roller 58 encounters the radial notch or groove 18, at which time a slight longitudinal movement of the scanner drum (due to compression spring 78) causes the roller 58 to positively engage the radial notch 18 to preclude any further relative motion, and to afford a fixed positive driving action for the scanner drum.

The principal purpose of spring 78 is to provide an elastic medium through which a longitudinal force is supplied to the scanner drum, particularly after the drum has been brought up to proper rotational speed. The spring 78, therefore, produces a biasing force on the scanner drum in the direction of the clutch mechanism so as to definitely cause the roller 58 to firmly seat in the radial groove 18 and to be firmly held in that position to prevent any relative motion between the clutch mechanism and the scanner drum. During the operation of the machine, the spring 78, therefore, maintains sufficient longitudinal force on the scanning drum to prevent relative movement between the scanner drum and the clutch mechanism which would, of course, destroy the proper phase relationship between these elements of the apparatus.

After the copy has been scanned and it is desired to change the copy on the drum, or if a plurality of drums are provided and it is desired to

change printer drums, replacing the one in the machine with a new drum on which is mounted a new copy to be scanned, it is only necessary to depress the button 112 which operates to rotate the pawl 94 in a clockwise direction around the pivot 108. This results in disengagement of the pawl 94 from the annular ring 90 (see Figure 2), and by reason of the spring 84, the rod 70 is returned to its "off" or inoperative position. When this occurs, the force of the spring which is transmitted through the annular driven member 42 to the clutch face 50, and from there to the scanner drum, causes the scanner drum to move to the right, completely disengaging the clutch, the inertia being sufficient to cause the scanner drum to fall off the spindle 26. At the same time, the shaft 70 has moved longitudinally an amount sufficient to completely release the opposite end of the scanner drum. The scanner drum then drops a slight amount and is caught by the semi-circular support brackets 114 and 116, the former cooperating with the clutch end of the scanner drum, and the latter cooperating with the opposite end of the scanner drum. Since the scanner drum was initially spinning at its normal scanning rate at the time it was released, the drum will continue to rotate in the semi-circular arms of the support brackets 114 and 116 until the energy is dissipated by friction between the drum and the support brackets. The drum may then be removed manually from the apparatus, and a new drum (or the same drum loaded with a new copy) positioned upon the stationary support brackets 114 and 116. With the drum in such a position, it is then only necessary to operate the member 96 through two steps, one of which brings the drum up to its proper operating speed, as described above, and the other finally brings the drum into cooperating with the roller 58 to thereby assure proper framing of the drum with respect to the driving mechanism and to thereby provide a positive driving medium.

It will be noticed in Figures 1 and 2 that the paper holding means 12 provided on the drum occupies the same annular position as the radial groove 18. It is not necessary that this relationship be present; however, some phase relationship must exist in order that the picture signals produced by the scanning operation may be properly phased with respect to the synchronizing or framing impulses that are produced by mechanism, not shown, associated with the transmitter driving mechanism.

Figure 4 shows a perspective view of the clutch end of the scanner drum, and in this view the bearing surface 13, the radial notch 18, and the paper holding means 12 are clearly shown.

From the foregoing it may be seen that a new and improved clutching arrangement for facsimile transmitters has been provided, whereby it is possible to remove the scanner drum from the transmitter without the necessity of actually stopping the transmitter. This is of particular advantage, since changing of the drum occupies only a relatively short space of time, and if the entire transmitter mechanism were stopped, naturally the receivers will lose frame and synchronism completely so that it would be necessary to reframe and again synchronize the receivers when the transmitter was again started to transmit the next particular copy.

It is apparent that the arrangement shown and described above may be used in any facsimile transmitter of the rotating drum type, and, furthermore, it is likewise evident that the same

mechanism may, in fact, be used in a facsimile receiver of the type where the recording is produced on a rotating cylinder, for example, by optical or other means in a manner familiar to those skilled in the art.

The present invention finds particular use in facsimile duplicators where one or more facsimile reproductions of a particular copy may be desired, and where it is desirable to frequently and rapidly change the subject matter being scanned and reproduced. In such duplicators, the printing mechanism is generally directly coupled to the scanning mechanism and may, in fact, be rigidly coupled to the shaft 26 shown in Figures 1 and 2. In such a mechanism, no synchronizing or framing impulses are necessary, since both the transmitter and receiver operate as a unit, but it is still vital that the scanner drum 10 bear a predetermined rotational position with respect to the printer drum, and more particularly, with respect to the helix on the printer drum. When the apparatus is used in connection with a facsimile duplicator, the worm drive shown in Figure 1 for rotating shaft 118 may be used to impart motion to the scanning head, or to drive the paper feed mechanism in a manner such as shown and described in Blain applications Serial No. 464,094, filed October 31, 1942, and Serial No. 460,615, filed October 3, 1942.

Although the present invention is described somewhat in detail as to mechanical features, it is to be understood that various and divers modifications may be made in the present invention without departing from the spirit and scope thereof, and it is desired that any and all modifications be considered within the purview of the present invention except as limited by the hereinafter appended claims.

Having now described my invention, what I claim is:

1. A facsimile apparatus including a drum member, driving means for rotating said drum including a motor and clutch assembly, a head spindle associated with said clutch assembly for supporting one end of said drum, said clutch assembly including a clutch face arranged to cooperate with said drum, and means for moving said drum longitudinally on said head spindle to engage the drum with the clutch face whereby said drum may be driven by the driving means.

2. A facsimile transmitting apparatus including a scanner drum, driving means for rotating said scanner drum including a motor, a clutch assembly interposed between said motor and said scanner drum, a head spindle associated with said clutch assembly for supporting one end of said drum and for maintaining axial alignment of said drum and clutch assembly, said clutch assembly including a spring pressed clutch face arranged to cooperate with said drum, and means for moving said drum longitudinally on said head spindle whereby the end of said drum may be brought into engagement with said clutch face to rotate said drum by said motor.

3. A facsimile apparatus including a drum, driving means for rotating said drum including a clutch assembly, a head spindle associated with said clutch assembly for supporting one end of said drum, a tail assembly for supporting the other end of said drum, said clutch assembly including a driving and a driven clutch member, spring means for normally engaging the driving and driven members whereby the driven member may be rotated by said driving member, a second clutch face associated with said driven

member, said second clutch face being arranged to cooperate with said drum, and means to move said drum longitudinally on said head spindle to engage the drum with said second clutch face whereby said drum may be rotated by said driven member.

4. A facsimile apparatus including a scanner drum, driving means for rotating said drum including a motor and clutch assembly, a head spindle associated with said clutch assembly for supporting one end of said drum, a tail stock assembly for supporting the other end of said drum, said clutch assembly including a driving and a driven clutch member, spring means for causing the driving and driven members to be normally engaged whereby the driven member may be rotated by said driving member, a second clutch face associated with said driven member, said second clutch face being arranged to cooperate with said drum, means including said tail stock to move said drum longitudinally on said head spindle to engage the drum with said second clutch face whereby said drum may be rotated by said driven member, and means including said tail stock to further move said drum longitudinally against the action of said spring means to thereby disengage said driving member from said driven member to permit relative rotary movement of the drum with respect to said clutch assembly.

5. Apparatus such as defined in claim 4 wherein said clutch assembly also includes a projection attached to said driving member and rotatable therewith, said projection being mounted to cooperate with the end of said scanner drum, a recess in the end of said scanner drum for receiving said projection, whereby said scanner drum may be driven by said projection when said driving member is disengaged from said driven member.

6. Apparatus such as defined in claim 4 wherein in said clutch assembly also includes a roller attached to said driving member and rotatable therewith, said roller being arranged to cooperate with the end of said drum, a recess in the end of said drum for receiving said roller, whereby said drum may be driven by said roller when said driving member is disengaged from said driven member and whereby a predetermined orientation of the drum with respect to the clutch assembly may be maintained.

7. A facsimile transmitting apparatus including a scanning drum, driving means for rotating said drum including a motor and a clutch assembly, a head spindle associated with said clutch assembly for rotatably supporting one end of said drum, a tail stock assembly for rotatably supporting the other end of said drum, said clutch assembly including a driving and a driven clutch member, means for rotating the driving member by said motor, spring means for normally causing the driving and driven members to be engaged whereby the driven member may be rotated by said driving member, a second clutch face associated with said driven member, said second clutch face being arranged to cooperate with the said one end of said scanner drum, means including said tail stock assembly for moving said drum longitudinally on said head spindle to thereby engage the scanner drum with said second clutch face whereby said drum may be rotated by said driven member, and means including said last named means for further moving said drum longitudinally against the action of said spring means to disengage

said driving member from said driven member to thereby permit relative rotary movement of the scanner drum with respect to the driving member of said clutch assembly.

5 8. Apparatus such as defined in claim 7 wherein said clutch assembly also includes a roller attached to said driving member and rotatable therewith, said roller being mounted with its axis of rotation normal to the rotational axis of said clutch assembly and arranged to cooperate with the end of said scanner drum, a radial recess in the end of said scanner drum for receiving said roller, whereby said drum may be driven by said roller when said driving member is disengaged from said driven member and whereby a predetermined orientation of the drum with respect to the driving member of the clutch assembly may be maintained.

9. A facsimile apparatus including a drum, 20 means for normally supporting said drum between a rotating clutch assembly and a tail stock assembly, said drum being provided at each end with an axial recess, a head spindle associated with such clutch assembly and a tail spindle associated with said tail stock assembly for cooperating with the axial recesses in said drum, means for moving said tail stock spindle longitudinally towards said clutch assembly a predetermined amount to cause said spindles to engage said recesses to thereby support said drum and to lift said drum from said normal support means, said clutch assembly including a clutch face arranged to cooperate with one end of said drum, said longitudinal movement being effective to cause said drum to move longitudinally on said head spindle to thereby cause the drum to engage said clutch face whereby said drum may be rotated by said clutch assembly.

10. Apparatus such as defined in claim 9 40 wherein said clutch face is attached to a driven member, a rotating driving member, a second clutch arrangement between said driving member and said driven member, spring means for normally causing engagement of said second clutch to cause the driven member to be rotated by said driving member, and means including said tail stock assembly for imparting a second longitudinal movement to said drum in the direction of the clutch assembly to thereby stress said spring 45 to disengage said second clutch whereby said drum may rotate relative to said driving member.

11. Apparatus such as defined in claim 9 wherein said clutch face is attached to a driven member, a rotating driving member, a second clutch arrangement between said driving member and said driven member, spring means for normally causing engagement of said second clutch to cause the driven member to be rotated by said driving member, means including said tail stock assembly for imparting a further longitudinal movement to said drum in the direction of the clutch assembly to stress said spring and to thereby disengage said second clutch whereby said drum and driven member may rotate relative to said driving member, and means including a projection attached to said driving member, the projection being positioned to cooperate with a recess in said drum whereby a predetermined desired orientation of the drum with respect to said driving member may be maintained.

12. A facsimile transmitting apparatus including a scanner drum, bracket means for normally supporting said drum in a stationary manner between a rotating clutch assembly and a 75 slide tail stock assembly, said drum being pro-

vided at each end with a circular axial recess, a head spindle associated with said clutch assembly and a tail spindle associated with said tail stock assembly for cooperating with the axial recesses, means for sliding said tail stock spindle longitudinally a predetermined amount towards said clutch assembly to cause said spindles to engage said recesses to thereby lift said drum from the bracket support means whereby the drum may be supported by said spindles, said clutch assembly including a friction clutch face arranged to cooperate with one end of said drum, said predetermined longitudinal movement of said drum on said head spindle being effective to engage the said one end of the drum with said clutch face whereby said drum may be rotated by said clutch assembly.

13. Apparatus such as defined in claim 12 wherein said clutch face is attached to a driven member, a rotating driving member, a second clutch arrangement between said driving member and said driven member, spring means for normally causing engagement of said second clutch to cause the driven member to be rotated by said driving member, means including said tail stock assembly for imparting a second longitudinal movement to said tail stock spindle and drum in the direction of the clutch assembly to thereby stress said spring to disengage said second clutch whereby said drum and driven member may rotate relative to said driving member, and means including a roller attached to said driving member, said roller being positioned to cooperate with a radial recess in the said one end of said drum whereby the second longitudinal movement will cause said roller to engage the recess to provide a positive driving action and to maintain a desired orientation of the drum with respect to said driving member.

14. A tail stock assembly for a facsimile apparatus including a longitudinally movable spindle, spring means for urging said spindle in a retracted position, a ratchet member slidably positioned on said spindle, spring means for urging said ratchet along said spindle in a predetermined direction, pawl means for engaging said ratchet to longitudinally move said spindle against the action of said first named spring by driving force transmitted through said second spring, said pawl means being adapted to engage a second step on said ratchet to longitudinally move said spindle further from its retracted position against the action of said first spring, and means for retaining said ratchet and spindle in either of the two positions.

15. A tail stock assembly for a facsimile transmitting apparatus including a longitudinally movable spindle, a first spring means for urging said spindle in a predetermined retracted position, a two step ratchet member slidably positioned on said spindle, a second spring means for urging said ratchet along said spindle in a predetermined direction, a pawl positioned to engage a first step on said ratchet to longitudinally move said spindle against the action of said first named spring by driving force transmitted through said second spring, said pawl, when retracted, being adapted to engage a second step on said ratchet to longitudinally move said spindle further from its retracted position against the

action of said first spring, and means cooperating with said ratchet for retaining said ratchet and spindle in either of the two positions, said retaining means being pivoted whereby the ratchet 5 may be released in order that the spindle may be returned to its retracted position by said first named spring.

16. A facsimile apparatus including a continuously rotating driving member, a clutch assembly associated with said driving member including a driven member, cooperating clutch faces between said driving member and said driven member, spring means for normally engaging said clutch faces to rotate said driven member by said driving member, a drum, a second clutch face on said driven member arranged to cooperate with said drum, a head spindle associated with said clutch assembly for supporting one end of said drum, a tail spindle for supporting the other end of the drum, means for longitudinally moving said tail spindle and said drum whereby said drum may engage said second clutch face on said driven member to thereby cause rotation of said drum, means for imparting further longitudinal movement to said tail spindle and to said drum to stress said clutch spring to thereby disengage said driving member from said driven member in order that said drum and driven member may rotate relative to said driving member, and means responsive to the latter longitudinal movement of said drum for providing positive driving engagement between said drum and driving member.

17. A facsimile transmitting apparatus including a continuously rotating driving member, a clutch assembly associated with said driving member including a driven member, cooperating clutch faces between said driving member and said driven member, spring means for normally engaging said clutch faces to rotate said driven member by said driving member, a scanner drum for supporting the subject matter to be scanned, a second clutch face on said driven member arranged to cooperate with one end of said drum, a head spindle associated with said clutch assembly for rotatably and slidably supporting one end of said drum, a longitudinally movable tail spindle for supporting the other end of the drum, means for longitudinally moving said tail spindle and said drum whereby said drum may slide on said head spindle to engage the end of said drum with the clutch face on said driven member to thereby rotate said drum, means for imparting a further longitudinal movement to said tail spindle and to said drum to stress said clutch spring to thereby disengage said driving member from said driven member in order that said drum and driven member may rotate relative to said driving member, a roller attached to said driving member, said roller being positioned with its axis of rotation normal to the axis of said head spindle and arranged to cooperate with the end of said drum, a radial recess in the end of said drum, whereby the relative rotation of the drum with respect to the driving member will permit engagement of the roller with the recess in the end of the drum to provide a positive drive and assure a predetermined orientation of the drum with respect to the driving member.
